ATTORNEY.

UNITED STATES PATENT OFFICE

HILMAR J. MILLER, OF ST. LOUIS, MISSOURI

LIGHT HOLDER FOR CHRISTMAS TREES

Application filed October 5, 1927. Serial No. 224,073.

My invention relates to light holders for Christmas trees in which two pairs of jaw members operate in conjunction with a spring member; and, the objects of my invention are, 5 first, to provide one pair of jaws at one end of the holder for clamping the device to the branch of a Christmas tree in any desired position; second, to provide a second pair of jaws at the opposite end of the holder for 10 holding a light, and, more particularly an electric light by the socket thereof, although not necessarily limited thereto, as candles can be held thereby, if so desired; and, third, to afford facilities for holding the light in any 15 one of three positions with relation to the longitudinal axis of the holder.

A further object of the invention is the provision of a light holder for Christmas trees, which possesses advantages in points of 20 simplicity and efficiency, and at the same time proves itself comparatively inexpensive in cost of manufacture.

With the above and other objects in view, the invention consists in the novel features 25 of construction, arrangement and combination of parts hereinafter more fully described and finally pointed out in the claim hereto appended.

Referring to the accompanying drawings 30 forming a part of this specification, wherein like characters of reference denote similar parts throughout the several views:

Fig. 1, is a view of the light holder shown 35 as applied to the branch of a Christmas tree and supporting an electric light. The light is shown in full lines in one position and in dotted lines in two other positions.

Fig. 2, is a side elevation of the holder embodying the features of my invention with 40 portions thereof broken away.

Fig. 3, is an inside plan view of the double jaw member.

Fig. 4, is a side elevation of the hinged jaw member which assists in holding the lamp 45 socket, or light, in position.

The device embodying the invention is made of metal stampings and comprises two clamp members designated A and B. These members A and B are at their tree branch gripping ends 1 and 2, respectively, of 50 counterpart shell shape construction to form jaws to grip the branch 3 of a Christmas tree. The members A and B are provided at their side marginal edges with ears 4 and 5, respectively, which are so arranged that the ears 4 of member A will engage between the ears 5 of member B. A pin 6 passes through the overlapping portions of the ears 4 and 5 serving to pivotally connect the members A and B. 60

The opposite end of member A is formed to provide a stationary jaw 7, which has its marginal edge flanged outwardly as at 8, and scalloped to both strengthen the jaw and to render it ornamental as well. 65

Associated with the stationary jaw 7 of member A is a movable jaw C, which jaw has a lower extension 9 terminating in a hinge lip 10 that passes through an opening 11 in member A and folded over, as at 12 to provide a hinge joint connection for the jaw C with the member A to permit movement of jaw C with relation to jaw 7. The inner faces of the jaws 7 and C have longitudinally curved portions 13 and 13', respectively, and they further have transversely curved portions 14 and 14' respectively, all of which curved portions serve to provide gripping faces for holding an electric light socket 15 therebetween against displacement, or a candle, if desired. Jaw C has a scalloped flanged edge 8'. 75

A suitable wire spring 16 is coiled about the pin 6 and is provided with finger portions 17 and 18 which extend upwardly in 80 diverging relation and bear against the outer face of members C, the inner face of a finger extension 19 of member B and exert pressure in outward directions at points above the pivot pin 6, thus yieldingly holding the lower 85 90

or ends of the branch gripping jaws 1 and 2 of the members A and B in engagement with the branch 3 of a Christmas tree and the jaws 7 and C in engagement with an electric light socket, or other lighting means.

In order that there may be sufficient roughened surface provided at the contacting portions of the branch gripping jaws 1 and 2 without however incurring any liability of series injury to the tree limbs engaged by the jaws 1 and 2, the marginal edges of the jaws 1 and 2 are scalloped and the outer faces of the body portion of the jaws are shaped to give a shell effect to the jaws, thus providing ornamental as well as strengthened branch gripping jaws, as is manifest.

It is evident that the holder may be held upon the limb of a tree at various angles thereto without slipping thereon, that it may be applied to the limb by pressing the upper end 19 of member B toward member 1 to relatively separate the gripping or contacting ends of the shell shaped jaws 1 and 2. When pressure upon the upper end 19 of member B is released, the spring 16 will automatically close the jaws 1 and 2 to firmly contact or grip the limb of the tree to which the device is applied and to hold it against displacement thereon.

It will be apparent from Fig. 1, that the light socket may be held between the jaws 7 and C in any one of three positions as shown in full lines designated D, and in dotted lines E and F.

From the foregoing description, it is apparent that I provide a light holder, which is highly efficient for the purpose intended and which has two stationary jaws and two movable jaws with the movable jaws operable independent of each other and both held in their closed position by means of a single spring.

The many advantages of the herein described invention will readily suggest themselves to those skilled in the art to which it appertains.

From the foregoing description, it is evident that a simple device for this purpose has been disclosed, but it is to be understood that I do not desire to restrict, or limit myself to the very details of the construction shown and described, which is merely illustrative, it being obvious that changes, not involving the exercise of invention, may be made without conflicting or departing from the spirit of the invention within the scope of the appended claim.

What I claim is:

A light holder for Christmas trees composed of one long plate and a relatively short plate pivoted to each other, the lower end of said long plate and the relatively short plate adapted to grip a tree branch for supporting the holder, a concaved recess formed upon the inner face of the upper end of said long

plate, a second relatively short plate hingedly connected to the long plate, a concaved recess formed in the inner face of the upper end of the second relatively short plate directly opposite the recess in the long plate for supporting a light and a resilient member adapted to exert pressure against both of the relatively short plates.

Signed in the city of St. Louis and State of Missouri.
